UNITED STATES PATENT OFFICE.

JAMES P. McDANIELS AND JOHN L. SWAN, OF HODUNK, MICHIGAN.

TELLURIAN.

SPECIFICATION forming part of Letters Patent No. 644,626, dated March 6, 1900.

Application filed October 31, 1899. Serial No. 735,415. (No model.)

To all whom it may concern:

Be it known that we, JAMES P. McDANIELS and JOHN L. SWAN, citizens of the United States, residing at Hodunk, in the county of Branch and State of Michigan, have invented 5 a new and useful Tellurian, of which the following is a specification.

Our invention relates to improvements in tellurians; and the object in view is to provide an improved and simple construction embracing a number of elements operable from a single source of power to indicate the yearly orbit of the earth around the sun, the inclination of the earth's axis to the plane of the 15 earth's yearly orbit, and the orbital motion of the moon around the earth and the travel of the moon with the earth around the sun, thereby demonstrating the changes of day and night, the change in the seasons of the year, 20 the cause of eclipse of the moon, the tides, and other phenomena.

With these ends in view the invention consists in the construction and combination of parts, which will be hereinafter fully described 25 and claimed.

In the drawings, Figure 1 is a plan view of a tellurian constructed in accordance with our invention. Fig. 2 is a vertical sectional elevation taken in the plane of the dotted line 30 22 on Fig. 1. Fig. 3 is a detail sectional elevation of the means for rotating the earth-globe on its axis and for rotating the support for the earth-globe.

The same numerals and letters of reference 35 are used to indicate like and corresponding parts in the several figures of the drawings.

The operating parts of the tellurian are supported in an elevated position by a suitable base 5. A vertical stationary spindle 6 projects upwardly from the center of the base, to which the spindle is firmly secured by any suitable means, and this spindle is provided with a solid bearing 7, arranged above the base. A hollow revoluble column is fitted 45 loosely on the spindle to rotate freely thereon, said column being externally of angular or polygonal form for the secure attachment of a horizontal table 9 thereto; but the contour of the column is not material, because its 50 shape can be varied and the table secured by any suitable means. The column extends

from the bearing 7 of the spindle nearly to the upper end of the spindle itself, and the table is arranged to rotate with the column in a horizontal plane and on a vertical axis 55 which is afforded by the spindle 6. This revoluble horizontal table is provided with a peripheral series of beveled gear-teeth 10, with which engages a beveled master-gear 11, which is fixed to a horizontal driving-shaft 12. Said 60 shaft is journaled in suitable bearings 13, preferably on the under side of the base 5, and a hand-crank or other power appliance 14 is secured to this shaft for the purpose of rotating the master-gear and the horizontal 65 table 9. On the upper surface of this table is provided an annular gear-track 15, which is located to one side of the spindle 6, so that the imaginary axis of the gear-track is eccentric to the axis of the table. Of course the 70 gear-track travels with the table when it is rotated by the master-gear, and thus the gear-track moves with the table around the spindle, so as to lie at the same distance therefrom at all points in the rotary travel of the 75 table.

16 designates a short vertical post which is provided at its lower end with a pintle 17, the latter being fitted revolubly in an opening of the table and at the center or axis of the annular track 15, whereby the post is arranged concentric with said gear-track. The post is, furthermore, provided at its upper end with an integral inclined arm 18, which extends in an upward and outward direction from the 80 post, and in this arm is journaled the axial spindle or arbor 19, which supports a globe or sphere E, representing the earth. Said axial arbor is mounted on the inclined arm of the post to lie at an inclination of twenty-three 85 and one-half degrees to the perpendicular, or approximately so, and to the lower extremity of the arbor is fastened a beveled gear-wheel 20. A horizontal shaft 21 is journaled in the post 16, below the inclined arm thereof, one 90 end of said shaft being provided with a bevel-gear 22, which meshes with the bevel-gear 20 on the earth-arbor. The other end of this horizontal shaft 21 has a spur gear-pinion 23, which meshes with a spur-gear 24 on another 95 horizontal shaft 25, also journaled in the post 16 and in parallel relation to the shaft 21, said

gear 24 meshing with the teeth of the annular gear-track 15 on the revolute table.

The pintle 17, which revolubly supports the post 16 on the table, is extended through the latter a suitable distance to receive a spur gear-pinion 26. A fixed gear 27 is secured on the stationary spindle 6, above the bearing 7 thereon, for the revolute table to rest loosely on said gear, and an intermediate gear 28 is mounted idly on the under side of this table 9 to have intermeshing engagement with the stationary gear 27 and with the gear 26 on the pintle of the post 16. The described gearing serves to rotate the post 16 on a vertical axis 15 and the earth globe or sphere E on an inclined axis when the table 9 is rotated by the driving-shaft. It is to be observed that the post 16 travels with the table around the gear 27, and this causes the gears 28 26 to turn the post 16 on a vertical axis. The rotation of the post insures the travel of the gear 24 around the annular gear-track 15, and this gear 24 is thus turned in order to propel the shaft 21, which in turn rotates the arbor 19, so that the earth-globe E will be rotated on its axis.

The globe or sphere S, emblematical of the sun, is mounted in a fixed or idle position on the hollow column 8, said sun globe or sphere being arranged, preferably, in the horizontal plane of the earth's sphere or globe.

The moon in our tellurian is indicated by the letter M, which is a globe of smaller diameter than the spheres indicative of the earth and the sun, and this moon-sphere is mounted and operated to travel around the earth-sphere and to partake of the orbital motion of the earth's sphere around the sun's sphere. The globe M is carried by a curved arm 29, which is provided with an angular end 30^a, the latter fitted loosely in the outer end portion of a horizontal carrying-arm 31, the latter being made fast with the upper extremity of the hollow revolute column 8. A stationary gear 32 is made fast with the upper extremity of the spindle 6 at a point above the horizontal arm 31, and to the end 30^a of the curved arm 29 is fastened a small gear-pinion 33. One or more intermediate gears 34 are mounted idly on the horizontal arm 31 in positions to mesh with the gears 32 33, and as the gear 32 is stationary, while the other gears of the train travel with the arm 31 as the latter rotates with the column 8, the gear 33 will be propelled to make the curved arm 29 and the moon's sphere pursue an orbital path around the earth's sphere E.

The travel of the post 16 and the earth-globe thereon, with the table, around the sun's sphere indicates the yearly orbit of the earth 60 around the sun to effect the change of seasons; but at all points in the orbital travel of the earth-globe the axial spindle thereof remains in an inclined position to the plane of the earth's orbit. The trains of gearing from the 65 stationary element 27 to the inclined spindle of the earth-globe insure the rotation of the

earth on its axis for effecting the change of night to day, and vice versa. The moon's sphere travels with the horizontal arm and the column, so that the moon partakes of the yearly orbit of the earth around the sun, and at the same time the moon's sphere is propelled at a speed to pursue an orbital path around the earth's sphere, thus demonstrating the cause of eclipses.

Our tellurian has its elements organized to illustrate the changes of day and night, the seasons of the year, variations in the tides, and the causes of eclipses.

Changes within the scope of the appended claims may be made in the form and proportion of some of the parts, while their essential features are retained and the spirit of the invention is embodied. Hence we do not desire to be limited to the precise form of all the parts as shown, reserving the right to vary therefrom.

Having thus described the invention, what we claim is—

1. A tellurian comprising a non-revolute spindle, a hollow column fitted loosely on the spindle, an emblem representative of the sun on the said column, a sphere emblematical of the earth and having an orbital path around the sun-emblem, a carrying-arm fast with the upper end of the hollow column and normally overhanging the earth-sphere, an arm journaled on the carrying-arm and supporting an emblem representing the moon adapted to pursue an orbital path around the earth-sphere, for the purpose described, substantially as set forth.

2. A tellurian comprising a non-revolute spindle, a hollow column fitted loosely thereon, a table fast with the column, means for rotating said table, a sphere mounted on the table to travel therewith and having means for rotating the same on its axis, a horizontal arm fast with the column, a curved arm journaled in the horizontal arm and carrying an emblem indicating the moon, a stationary gear fast with the spindle, and other gears between the stationary gear and the curved arm, substantially as described.

3. A tellurian, comprising a base, a vertically-disposed fixed spindle supported thereby, a hollow column fitted loosely on the spindle, an emblem representing the sun carried by said column, a circular table fixed to the hollow column, and having a peripheral series of gear-teeth, a master-gear mounted upon the base, means for operating the master-gear, a gear fixed to the fixed spindle, an inclined spindle mounted upon the table, located eccentric with respect to the fixed spindle and traveling with the table about the sun-emblem, an earth-emblem independently revolute upon the inclined spindle, a train of gears between the inclined spindle and the fixed gear, and also carried by the table, a carrying-arm fixed to the hollow column and alined normally above the sun and earth em-

blems, a bowed arm loosely journaled in the carrying-arm and having an orbital path around the earth-emblem, a moon-emblem fixed to the latter arm, a fixed gear carried by the fixed spindle, and a train of gears between the said fixed gear and the moon-arm, and mounted upon the carrying-arm.

5 In testimony that we claim the foregoing as

our own we have hereto affixed our signatures in the presence of two witnesses.
